CLAIM

The ornamental design for a filter package, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of an embodiment of a filter package having a blue bottom portion;

FIG. 2 is a front side elevational view thereof;

FIG. 3 is a back side elevational view thereof;

FIG. 4 is a left side elevational view thereof;

FIG. 5 is a right side elevational view thereof;

FIG. 6 is a top planar view thereof;

FIG. 7 is a bottom planar view thereof;

FIG. 8 is a perspective view of the filter package of FIG. 1, wherein a top portion and the blue bottom portion of the filter package are illustrated in a separated orientation;

FIG. 9 is a front side elevational view thereof;

FIG. 10 is a back side elevational view thereof;

FIG. 11 is a left side elevational view thereof;

FIG. 12 is a right side elevational view thereof;

FIG. 13 is a top planar view thereof; and,

FIG. 14 is a bottom planar view thereof.

The broken lines form no part of the claimed design.
